VENTILATING FAN

William A. Lenz, Lebanon, Mo.

Application September 18, 1930

Serial No. 482,832

3 Claims. (Cl. 230—134)

The present invention relates to ventilating fans or air impellers, and aims to provide a fan or impeller of novel and improved construction for creating a current of air.

5 Another object of the invention is the provision of a fan or impeller which will run smoothly and noiselessly, as well as efficiently, and which may be placed over a desk or table without disturbing papers or other light articles that may be lying 60 on the desk or table, the fan or impeller delivering air radially in all directions about a vertical axis.

With the foregoing and other objects in view, which will be apparent as the description proceeds, the invention resides in the construction and arrangement of parts, as hereinafter described and claimed, it being understood that changes can be made within the scope of what is claimed, without departing from the spirit of the 70 invention.

20 The invention is illustrated in the accompanying drawing, wherein—

Figure 1 is a plan view of the fan or impeller within a cabinet, the cabinet and other portions 75 being shown in section.

Fig. 2 is a vertical section taken on the line 2—2 of Fig. 1, portions being shown in elevation.

Fig. 3 is a perspective view of a table or desk type of fan having a "double" impeller which is 80 a slight modification of the double impeller shown in Figs. 1 and 2.

Fig. 4 is a perspective view of a table or desk type of fan embodying a "single" impeller.

With respect to the device shown in Figs. 1 85 and 2, this application is a division of application Serial No. 375,475, filed July 2, 1929, the fan or impeller being employed within a cabinet 1 which encloses the fan and its driving means, and said cabinet may be of wood, sheet metal or other 90 suitable material, and is provided therein with the fan or blower casing 2 in which the fan or blower 95 is mounted for rotation.

The casing 2 is preferably of sheet metal and has a broad discharge opening 4 at the front of 45 the cabinet 1, with the diverging walls 5 and 6 at the opposite sides of said opening. The casing 2 is disposed horizontally for directing a broad stream of air in a horizontal plane, and the fan 3 is located nearer the wall 5 than the wall 6, and 50 said casing has a curved wall 7 connecting the walls 5 and 6 and spaced increasing distances from the wall 5 to the wall 6, and the passage of 55 increasing width between said wall 7 and the fan 55 is in proportion to the increasing volume of air

flowing therein in the direction of the arrows as seen in Fig. 3.

The top of the casing 2 and housing 1 have an air inlet opening 8 and the bottom of said casing has an air inlet opening 9, said openings being 60 concentric with the fan and of larger diameter than the fan so that the fan may be moved through said openings into and out of the casing. Moreover, the openings being as large or larger 65 than the diameter of the fan will permit unrestricted flow of air into the fan, to avoid noise due to the inrush currents of air.

The fan or blower proper, or the rotor, is carried by a vertical shaft 10 whose lower end is journaled in a step bearing 11 on the bottom of 70 the cabinet, and the upper terminal of said shaft is journaled in a cross bar 12 secured on the top of the cabinet over the opening 8, said bar 12 being removable to permit the rotor to be lifted 75 from the cabinet.

The fan rotor comprises flanged collars or 80 hubs 13 secured by set screws or otherwise on the shaft 10, and angle iron or other suitable spokes 14 are riveted, welded or otherwise secured to the collars 13 and are offset from the axis of the shaft 10, as seen in Fig. 1. There are four pairs 85 of spokes, as shown, although there may be any suitable number according to the size of the rotor. Fan blades 15 of sheet metal or other suitable material are riveted or otherwise secured to the outer terminals of said spokes, and rings 16 extend across said spokes and across 90 the inner edges of the blades. Said blades have forwardly extending portions or flanges 17 at their inner edges bearing against and preferably secured to the rings 16, and it has been found 95 that such portions 17 are of advantage in dividing the air as said portions 17 move forwardly in advance of the blades 15, so that said blades will throw the air outwardly from the rotor or impeller more effectively, and said portions 17 also increase the air suction at the ends of the blades adjacent to the openings 8 and 9. Said portions 100 17 are curved to conform to the curvature of the rings 16.

The two streams of air entering the fan casing through the openings 8 and 9 are separated by flat segments or curved plates 18 having their ends flanged and riveted or otherwise secured to the blades 15, with said plates located between 105 the opposite ends of the rotor or impeller.

The rotor illustrated is a double impeller in that air is taken in at both ends, and in some instances a single impeller may be used having a disk at one end to which the blades are secured, 110

with a ring 16 at the opposite ends of the blades, and the spokes may or may not be used.

An electric motor 19 is disposed in the cabinet below the fan casing and is suitably connected to the fan shaft 10 for rotating the fan.

The rotor or impeller provides for a maximum volume of air current, without noise, and the air is spread across a considerable area. The fan may also be used with its axis horizontal, and may 10 also be used as an exhaust fan. The fan runs smoothly and noiselessly, as well as providing for high efficiency.

Fig. 3 illustrates a table or desk type of fan wherein the motor 19' serves as a base, and a 15 flanged collar 13' is secured on the upper end of the upstanding armature shaft of the motor and has angle irons or spokes 14' secured thereon, a single set of spokes being used instead of two sets as shown in Figs. 1 and 2. The fan blades 20 15' of sheet metal or other suitable material are riveted between their upper and lower ends to the outer terminals of the spokes, the spokes having flanges secured on the collar or disk 13' and having upstanding flanges to which the blades 25 are riveted or otherwise secured. The blades have forwardly extending portions or flanges 17' at their inner edges bearing against and secured to upper and lower rings 16', said portions 17' being curved to conform to the curvature of the 30 rings 16' about the axis of the impeller as a center.

Flat segments or curved plates 18' are provided 35 between the upper and lower ends of the blades, one end of each segment or plate being bent at an angle and secured to the corresponding blade and the other end overlapping and being secured to the lower horizontal flange of the corresponding spoke. The plates 18' are of a width substantially equal to the width of the blades, and 40 jointly provide an annulus which is intersected by the blades and along the inner edge of which the flanges 17' are disposed, with spaces between the forward edges of said flanges and the blades in advance through which the air may flow outwardly after flowing axially through the rings 45 16' into the impeller.

The fan may be operated on a table or desk to direct the air radially in all directions, to provide for efficient ventilation, without disturbing 50 papers or other light articles lying on the table or desk.

55

60

65

70

75

Figs. 1, 2 and 3 show "double" types of impellers, in that air is taken into the impeller axially from opposite directions, while Fig. 4 illustrates a "single" impeller, including a disk or plate 17" secured on the upstanding armature shaft of the motor 19", with the fan blades 15" and a single ring 16" below said plate. Air is taken upwardly into the impeller and distributed radially, there being a tendency to direct the air upwardly from the impeller. The impeller, however, may be inverted, with the blades above the plate so that the air is taken in downwardly, and there is a tendency to direct the air outwardly and downwardly from the impeller.

If desired, a suitable guard or cage (not shown) 80 may be placed around either of the impellers shown in Figs. 3 and 4.

Having thus described the invention, what is claimed as new is:

1. An impeller comprising narrow rings at each 95 end of the impeller, leaving an intermediate radially unobstructed circumferential area therebetween, blades extending outwardly from said rings, portions extending forwardly from the inner edges of said blades and curved to conform 100 to said rings and being of substantially the same width as the blade in an axial direction so as to divide the inwardly flowing air; and segment plates between the ends of the blades and located between the blades, the said plates extending inwardly only as far as the said rings.

2. An impeller comprising a shaft, spokes secured to said shaft, blades secured to said spokes, curved portions extending forwardly from the inner edges of the blades, rings secured to said 110 portions, and segment plates between said blades located between the ends thereof, the said plates extending inwardly only as far as the said rings.

3. In combination with a casing having its ends open and a discharge opening in its side portion, an impeller comprising a shaft, spokes secured to said shaft, blades secured to said spokes, curved portions extending forwardly from the inner edges of the blades, rings secured to said 115 portions, and segment plates between said blades located between the ends thereof, the said plates extending inwardly only as far as the said rings.
